UNITED STATES PATENT OFFICE.

GEORGE D. COREY, OF LOWELL, MASSACHUSETTS, ASSIGNOR OF ONE-HALF
TO WOODS, SHERWOOD & CO., OF SAME PLACE.

BOTTLE-STOPPER.

SPECIFICATION forming part of Letters Patent No. 294,443, dated March 4, 1884.

Application filed July 3, 1883. (No model.)

To all whom it may concern:

Be it known that I, GEORGE D. COREY, of Lowell, in the county of Middlesex and State of Massachusetts, have invented a new and 5 useful Improvement in Bottle-Stoppers, of which the following is a specification.

My improvement relates to bottle-stoppers for closing the mouths of bottles and other similar receptacles; and it consists in certain 10 improvements upon the bottle-stopper patented to M. J. Hinden in Patent No. 175,981, substantially as hereinafter described.

In the drawings, Figure 1 represents a vertical section of a bottle neck and mouth provided with my invention, and having the stopper secured upon the mouth of the bottle. Fig. 2 represents the same with the stopper raised from the mouth of the bottle. Fig. 3 is a top view of Fig. 1. Fig. 4 is a top view 20 of Fig. 2.

A is the bottle-neck. B is the bail of the stopper, which is secured to a band, C, passing around the neck of the bottle, and having coils c bent in it, into which the ends of the 25 bail B are sprung in the usual manner, as shown. On top of the stopper D is secured a metal plate, d², which has ears upon each side of it, and holes d³ in the ears, through which the bail-wire passes to attach the stopper to 30 the bail. These holes permit the stopper and plate d² to slide freely up and down the bail-wire sufficiently to cork and uncork the bottle, and they are further important in holding the 35 ends of the bail-wire into the coil c as the pressure is brought down upon the stopper, thus enabling the use of a more cheap and convenient attachment of the bail to the bottle. This is because the holes d³ in the ears entirely surround the bail-wire. D is the 40 bottle-stopper, which is formed with a flange, d, which overlaps the mouth of the bottle, and presses down upon its upper face when the stopper closes it. Attached to the stopper and plate d² is a vertical pin, e, which projects upward a short distance above the plate. Pivoted upon this pin is a disk E of metal, so as 45 to turn freely around it. This disk E has a slot, e², channeled or cut across it and passing across its axis, of sufficient width to allow the 50 bail-wire B to descend to its bottom. The

pivot e, on which the disk revolves, only comes up to the bottom of this slot. Attached to the disk E on one side is a thumb-piece, e³, which projects out horizontally sufficiently to enable the disk to be revolved by pressing upon it. 55 As will be noticed, this thumb-piece projects radially from the side of the disk close to one end of the slot e². At the end of the slot next this thumb-piece the wall of the opposite side of the slot is made cam-shaped, as shown in Fig. 1, while at the other end of the slot the wall on the same side of it as the thumb-piece is made cam-shaped in like manner, as shown in Fig. 2. This cam-shape of the opposite sides of the slot at its opposite ends extends to the 60 bottom of the slot and furnishes the means of closing the bottle tightly, as hereinafter described. The disk E is secured to the plate d² by heading down the pin e in the bottom of the slot e² sufficiently to prevent the disk from 65 slipping off the pin.

The operation of my device is as follows: Suppose the bottle to be uncorked in the positions shown in Figs. 2 and 4, and that it be desired to close its mouth. The plate d², carrying with it the stopper D and the disk E, is slipped down on the bail until the shoulder d of the stopper is seated on the mouth of the bottle. In this position the horizontal part of the bail will still remain in the slot e², the 70 length of the bail being so adjusted that it cannot quite come out of the slot. The bottle-stopper D and its shoulder d are made of india-rubber or other suitable elastic material; and it consists of a nose-piece, which enters and 75 fits the bottle-neck as well as the shoulder d, that rests on top of the neck. This nose-piece serves to aid in holding the stopper more steadily against the force applied to the thumb-piece e³ in stopping and unstopping the bottle, 80 and prevents the plate d² from binding upon the bail B. While in the position last described, pressure is applied to the thumb-piece e³, and the disk E is revolved in the direction 85 of motion of the hands of a watch. This brings 90 the cam-shaped sides of the slot e² to bear under the horizontal part of the bail on opposite sides of the disk, and the stopper D and its shoulder d yielding under the compression 95 thus produced, the continued rotation of the 100

disk carries its thumb-piece and slot into the position shown in Figs. 1 and 3, and compresses the stopper tightly upon and into the mouth of the bottle, the bail resting upon the 5 horizontal upper surface of the disk beyond the cam-shaped sides of the slot, which horizontal surface prevents the bottle from being unstopped until the disk is revolved backward, so as to bring the slot e^2 under the bail-wire. 10 The position of the thumb-piece e^3 is such with relation to the bail-wire that the latter serves to stop it at the proper points on opposite sides of the bail to completely and perfectly stop and unstop the bottle-mouth without any care 15 or attention on the part of the operator. The bail B, being pivoted in the band C, which passes around the neck of the bottle, can be swung entirely out of the way of the bottle-mouth when the stopper is raised, as shown 20 in Figs 2 and 4.

The advantages of my improved bottle-stop-

per are that it furnishes very great power to compress the stopper upon the mouth of the bottle; that all its parts are securely attached to the bail, and the latter to the wire-band around the bottle-neck; that it can be operated without the exercise of special skill on the part of the operator, and that it is simple and not liable to get out of order. 25

What I claim as new and of my invention 30 is—

The combination of the rotating disk E, having slot e^2 , with cam-shaped walls, the plate d^2 , having holes d^3 d^4 , surrounding the bail-wire, and the bail B, having its ends sprung into 35 holes in neck-band C, with the latter, substantially as described.

GEORGE D. COREY.
